CASK-PITCHING MACHINE.

1,122,537.

Specification of Letters Patent. Patented Dec. 29, 1914.

Application filed March 30, 1914. Serial No. 828,416.

To all whom it may concern:

Be it known that we, HENRY RAUCH and HARRY E. RAUCH, citizens of the United States, and residents of Mount Vernon, in the county of Westchester and State of New York, have invented certain new and useful Improvements in Cask-Pitching Machines, of which the following is a specification.

Our invention relates to apparatus employed for the purpose of applying hot liquid pitch or the like to the interior surfaces of beer barrels, casks, &c., and has for one of the principal objects to provide such an apparatus which shall be safe in operation; the invention being an improvement upon apparatus of the type set forth, for instance, in United States Letters Patent No. 599,476, granted to Henry Rauch on February 22, 1898.

An apparatus of the type which is the subject of the said Letters Patent No. 599,476 and of the present invention is designed to be operated by compressed air or similar means, which is admitted into the pitch receptacle and which forces the hot liquid pitch out through a spraying nozzle into the interior of the cask or other vessel which is to be interiorly coated or "pitched." In using such an apparatus it sometimes happens that a careless workman will turn on the compressed air when there is no barrel over the spraying nozzle, or will attempt to lift the barrel off the nozzle without shutting off the compressed air, thus allowing a quantity of hot pitch to be sprayed about the room, severely burning anyone within range of the spray.

One of the objects of our present invention is to provide means whereby the stop cock controlling the compressed air can only be opened when there is a barrel over the spraying nozzle.

The invention consists in the novel construction, arrangement and combination of various devices and parts as shown in the accompanying drawings and fully described in this specification.

In the accompanying drawings, Figure 1 is a sectional view of a pitching apparatus provided with our invention; Fig. 2 is a sectional view of a modified form of our invention adapted to be used with a pitching apparatus in which the handle controlling the compressed air stop-cock is moved in a horizontal, instead of a vertical plane, as shown in Fig. 1; and Figs. 3 and 4 are detail

plan views of a portion of the mechanism shown in Fig. 2, which are hereinafter more particularly described.

The main features of a cask pitching apparatus to which our present invention is applied are fully described in the said Letters Patent, No. 599,476, and need not be specified in detail here; and it will be sufficient to state, (referring more particularly to Fig. 1 of the present drawings), that 11 represents the kettle or reservoir to contain the pitch, which is mounted over a suitable furnace for heating the same.

Below the bottom of the reservoir or kettle 11 and preferably integral therewith is a tank 12, having an inlet 13 adapted to permit the flow of pitch from the reservoir 11, said inlet being controlled by a suitable valve opening downwardly or inwardly at 13.

A pipe 14 leading from some suitable source of compressed air or the like enters the top of the tank 12 and from a point near the bottom of the tank 12 an outlet pipe 15 extends upward through the receptacle 11 and bears at its upper end a perforated spraying nozzle 16. It will be readily understood that when the machine is operated, the tank 12 being full of liquid pitch, if compressed air is admitted through the pipe 14 it will exert pressure upon the upper surface of the pitch in the tank 12, forcing the same out through the pipe 15 and spraying the same into a barrel 17, which rests, during the operation, upon a suitable support 18, the pipe 15 extending upward through the bunghole. The liquid pitch covers the inner surface of the barrel, and the surplus drains down through the bunghole and flows into the receptacle 11.

The supply of compressed air is regulated by a three-way cock 32 which is operated by the lever 20, through the bar 28 and lever 31. When the lever is in the position shown in the dotted lines and indicated by the numeral 21, the compressed air which enters through that portion of the pipe 14 designated 22, has access to the tank 12 and forces the liquid pitch therein up through the pipe 15 in the manner hereinabove described, at the same time keeping the valve 13 closed against the weight of the pitch in the tank 11. When, however, the lever 20 is in the position shown in the full lines, the supply of compressed air is cut off and the tank 12 is in communication through

the pipe 14 with the outer air, the valve located at 13 then opening under the weight of the pitch in the reservoir 11, and refilling the tank 12.

5 It is obvious that the compressed air should never be turned on, except when a barrel is placed over the nozzle 16, and that the barrel should never be lifted from the support 18 without first shutting off the compressed air, as in either case a quantity of hot pitch would be sprayed out from the nozzle 16, severely burning, and perhaps killing the operator.

10 In carrying our invention into effect in the embodiment thereof shown in Fig. 1 I provide a pitching machine of the above described type having mounted upon the top thereof a suitable support 23, pivotally mounted in which is a lever 25 adapted to have one end 15 thereof depressed by the weight of a barrel placed upon the support 18. When thus depressed this lever will occupy the position shown by the dotted lines. In this lever, at the opposite end thereof from that depressed 20 by the barrel, is a recess 26.

15 It will be seen by reference to the drawing (Fig. 1) that the lever 20 is L-shaped, and pivotally secured at its angle to the pipe 14 as shown at 19. One end of this lever terminates in a handle 27, while to the other end is pivotally secured a vertical rod 28. To the lower end of this rod 28 is pivotally mounted one end of a lever 31. This lever is pivotally mounted at its center portion on 25 the portion of the pipe 14 which carries the three-way cock 32. It will be understood that when the lever 20 is in the position shown by the full lines in the drawing, the rod 28 and lever 31 will also be in the position shown by the full lines, and when in 30 this position the free end of the lever 31 will be adapted to clear the lever 25 when said lever 25 is weighted by a barrel placed over the support 18, and this lever 25 is consequently in the position shown by the dotted lines, but to engage with the notch 26 in 35 said lever 25 when said lever is not weighted by a barrel, and consequently in the position shown in the drawing by the full lines.

40 The operation of this embodiment of our invention is as follows: When the lever 20 is in the position indicated by the full lines the bar 28 and the levers 24 and 31 will also be in the position indicated by the full lines, 45 as hereinabove described, and the compressed air will be shut off. If any attempt be made to depress the lever 20 and turn on the compressed air, without first placing a barrel on the support 18, it will be found 50 that the lever cannot be moved, as the lever 31 engages with the notch 26 in the lever 25 and the device is locked. If however a barrel is placed over the support 18, the end 55 of the lever extending toward this support 18 is depressed, and its other end provided

with the notch 26 will be correspondingly elevated. The lever 25 will then occupy the position shown by the dotted lines, and the lever 20 may then be moved over to the position shown by the dotted lines and indicated 60 by the reference numeral 21, the rod 28 and lever 31 at the same time assuming the position shown by the dotted lines and indicated respectively by the reference numerals 29 and 30. The lever 20 is prevented from 65 being moved too far by the stop 33, which strikes against the rod 28. When the device is in the position shown by the dotted lines the compressed air is turned on and the 70 pitch is forced out through the nozzle 16 and sprayed upon the inside of the barrel placed thereover. When the operation of 75 pitching the barrel is completed, the lever 20 should be moved back into the position shown by the full lines (when it will be prevented from moving too far by the stop 34, which strikes against the lever 31,) thus 80 shutting off the compressed air and at the same time causing the rod 28 and lever 31 to also assume the positions shown by the 85 full lines. If the barrel then be lifted off, the lever 24 will also fall into the position shown by the full lines, the notch 26 will reengage with the end of the lever 31, and the device will remain locked until another 90 barrel is placed over the support 18. If, however, a careless operator attempts to remove the barrel without shutting off the compressed air, the barrel strikes against the lever 20, (which is then in the position 95 shown by the dotted lines) and moves the same upward. If this lever 20 is moved upward to any extent, the weight of the bar 28 will cause the lever 20 to automatically 100 assume the position shown by the full lines, 105 the movement of the lever 31 raising the lever 25 sufficiently to allow the end of said lever 31 to engage with the notch 26 in the said lever 25, thus shutting off the compressed air and locking the lever 20. 110

115 The modified form of our invention shown in Figs. 2 and 3 will now be described. This form is adapted for use on that type of spraying machine having two spraying nozzles and a horizontally extending lever for the control of compressed air so constructed that when its outer end is in a position midway between said nozzles no compressed air is allowed to pass, but by moving said lever toward one of said nozzles the pitch is caused to spray from that nozzle. In this drawing it is unnecessary to show the entire machine, but we have, however, shown the upper portion of the apparatus, comprising a support for a barrel, 120 here designated 41, a spraying nozzle, here designated 40, a lever 42 for the control of the compressed air, rigidly mounted on the upper end of a rod 43, the lower end of this rod operating a three-way cock (not shown 125 130

in the drawings); and the safety device, hereinafter described. In carrying our invention into effect in this embodiment we provide a support 44, analogous to the support 23 of Fig. 1. On this support are pivotally mounted levers 46 adapted to assume the position shown by the dotted lines when barrels are placed on the supports 41, but otherwise adapted by the weight of their upper portions (designated 45) to assume the position shown by the full lines. The upper end of the rod 43 is journaled in a stationary guide 47, which is also provided with slots 48 in which the levers 46 may slide as a barrel is lifted on or removed from one of the supports 41. Rigidly mounted on the rod 43 is a projecting pin extending between the levers 46 and adapted, when both of these levers are in the position shown by the full lines, to prevent the rotation of the rod 43 in either direction. When, however, one of the levers 46 is in the position shown by the dotted lines, the rod 43 can be rotated in one direction, as the pin 49 will clear the lever when it is placed in such a position.

The operation of this embodiment of our invention is as follows: When the machine is not in use the levers 46 remain in the position shown by the full lines and the handle 42 cannot be moved. When, however, a barrel is placed upon one of the supports 41, the lower end of the lever 46 situated on that side of the machine is depressed, thus allowing the handle to be turned and the compressed air to be admitted to the tank which is situated under such support 41, and the barrel placed thereon to be sprayed. As long as the compressed air remains turned on, the barrel can not be lifted from the support, as the handle 42 is directly thereover. As soon, however, as the compressed air is shut off, the barrel may be lifted as the handle 42 is no longer in the way. As soon as the barrel is lifted off, the lever 46 reassumes the position shown by the full lines, and the device remains locked until another barrel is placed upon one of the supports 41.

Fig. 4 shows a modified form of the parts shown in Fig. 3. A handle 60 and upright rod 61 are provided, analogous to the handle 42 and rod 43 shown in Fig. 3. In Fig. 4, however, instead of one pin 49, two pins 62 and 63 are shown, and two guides 64 and

65 placed some distance apart, instead of the guide 47 of Fig. 2.

The advantages of our invention will be obvious from what has been above said concerning its construction and mode of operation.

Having thus described our invention what we claim as new and desire to secure by Letters Patent is as follows:

1. In a safety device for pitching machines, the combination with a pitching machine of the type operated by compressed air or the like, of a lever having one end adapted to be depressed by a barrel or the like placed thereon, and having its other end provided with a notch, means adapted to control the compressed air which operates the machine, a lever adapted to operate said means, one portion of said lever being adapted to engage with said notch, and means operatively connected with another portion of said lever, and adapted to move the same and thereby control said compressed air, said means comprising a bar pivotally connected to said second named lever, and an L-shaped lever pivotally connected to the other end of said bar.

2. In a safety device for pitching machines, the combination with a pitching machine of the type operated by compressed air or the like, of a lever having one end adapted to be depressed by a barrel or the like placed thereon, and having its other end provided with a notch, a three-way cock adapted to control the compressed air which operates the machine, a lever adapted to operate said three-way cock one portion of said lever being adapted to engage with said notch, and means operatively connected with another portion of said lever and adapted to move the same and thereby control said three-way cock, said means comprising a bar pivotally connected to said second named lever, and an L-shaped lever pivotally connected to the other end of said bar.

In witness whereof we have hereunto signed our names this 27th day of March 1914, in the presence of two subscribing witnesses.

HENRY RAUCH.
